UNITED STATES PATENT OFFICE.

WALTER THOMAS, OF YONKERS, NEW YORK, ASSIGNOR TO ALEXANDER SMITH & SONS CARPET COMPANY, OF SAME PLACE.

DESIGN FOR CARPET.

SPECIFICATION forming part of Design No. 35,053, dated September 3, 1901.

Application filed July 16, 1901. Serial No. 68,547. Term of patent 3½ years.

To all whom it may concern:

Be it known that I, WALTER THOMAS, of Yonkers, county of Westchester, State of New York, have invented and produced a certain 5 new and original Design for a Carpet, fully described and represented in the following specification and the accompanying drawing, forming a part of the same.

The design is intended to be worked into or upon carpets or similar fabrics in such colors as may be desired; and I do hereby declare that the drawing accompanying this specification conveys to one skilled in the art of carpet weaving and manufacture a clear understanding of the same and is sufficient to enable such person to use my invention.

The characteristic features of the design are the prominent flower-and-leaf clusters A, with ornamental forms B between the clusters.

What I claim as new, and desire to secure by Letters Patent, is—

The design for a carpet, substantially as shown and described.

In testimony whereof I have hereunto set 25 my hand in the presence of two subscribing witnesses.

WALTER THOMAS.
